ASSIGNORS OF ONE-EIGHTH TO HENRY L. HICKS, OF GREENSBORO, NORTH CAROLINA.

GRAVITY-SANDER FOR FRONT AND REAR DRIVE-WHEELS FOR LOCOMOTIVES.

1,116,925.

Specification of Letters Patent. Patented Nov. 10, 1914.

Application filed December 10, 1913. Serial No. 805,805.

To all whom it may concern:

Be it known that we, EDWIN A. RIVES and HARRISON B. NABORS, citizens of the United States, residing at Greensboro, in the county of Guilford and State of North Carolina, have invented certain new and useful Improvements in Gravity-Sanders for Front and Rear Drive-Wheels for Locomotives, of which the following is a specification.

Our present invention relates to track sanding devices, the object of our invention being the provision of a gravity sander for supplying sand to either the front or rear drive wheels, or both, of locomotives such as are now in the process of construction, the present device not being applicable to locomotives as now built without slight modification.

Fluid actuated sanders, particularly those operated by an air blast, are in common use at the present time but are objectionable, due to the fact that the air passing with the sand through the pipes leading to the rails passes with such force as to blow the sand from the rails over the track instead of applying it economically on the rails. Further the blast of mixed air and sand passing through the controlling valves and pipes rapidly scours out the valve casings and other connections, necessitating frequent renewal of parts.

Our present invention therefore comprehends the provision of a sander in which the sand is delivered to the rails immediately adjacent the drive wheels of the locomotive by gravity alone, thereby avoiding unnecessary waste of sand and wearing of expensive parts of the device.

A further object of our invention is to provide a sander which, while particularly adapted for use on locomotives, may be employed with equally good results on street or railway cars.

A further object of our invention is to provide means including a manually controlled valve for regulating the supply of sand to the rails, either in advance of the forward drive wheels of the locomotive, at the rear of the rear drive wheels, or at both points, in order that sand may be properly applied, irrespective of the direction of movement of the locomotive.

A still further object of our invention is to so construct the valve that sand will be delivered simultaneously and in substantially equal quantities to the drive wheels upon both sides of the locomotive, that is, to both rails of the track. And a still further object of our invention is to so construct the valve controlling the flow of sand that the valve itself forms a sand trap to prevent undue flow of sand from the sand dome, the movement of the valve being positively limited in order that it may at no time become inoperative.

With these and other objects in view, our invention will be more fully described, illustrated in the accompanying drawings, and then specifically pointed out in the claims which are attached to and form a part of this application.

In the drawings:—Figure 1 is a side elevation of a conventional locomotive, showing our improved sander in place; Fig. 2 is a detail sectional view taken through the sand dome and controlling valve; Fig. 3 is a vertical sectional view taken on the line 3—3 of Fig. 2, showing further details of valve construction; Fig. 4 is a perspective view of the valve removed from its casing; Fig. 5 is a detail sectional view on the line 5—5 of Fig. 2, showing the manner in which the sand passing from the valve is divided and supplied to both rails of the track; Figs. 6 and 7 are sectional views illustrating the two open positions of the valve, the valve in Fig. 6 being opened to discharge sand to the rear drive wheels, while that in Fig. 7 is opened to discharge sand to the forward drive wheels.

Corresponding and like parts are referred to in the following description and indicated in all the views of the drawings by the same reference characters.

In order to insure a clear and accurate understanding of our invention we have illustrated the same in connection with a conventional form of locomotive 10 having forward and rear drive wheels 11 and 12, respectively, and an engineer's cab 13.

The object of our present invention is to provide a gravity sander by means of which sand may be supplied to the rails 14 of the track either immediately in advance of the drive wheels 11 or immediately at the rear

of the drive wheels 12. With this object in view, we provide the locomotive with a sand dome 15 of the usual type with the exception that its transverse partition or false bottom 16 is further spaced from the boiler 17 of the locomotive, to which the sand dome is secured by rivets or other suitable fastening devices 18, than is customary. This bottom 16 may be formed integrally with the sand dome or as a separate part thereof as preferred. If the latter is the case, it will be supported in place upon suitable brackets 19 carried by the body portion of the dome.

15 The bottom of the sand dome is spaced a considerable distance above the boiler, as previously explained, in order to provide room in the base of the dome for the valve and its casing, indicated as a whole by the numeral 20. Sand is supplied to the valve from the dome by a pipe 21 leading through the central part of the bottom 16 of the dome into the valve casing. The valve casing includes a substantially cylindrical shaped body portion 22 closed at one side and a substantially circular face plate 23 adapted to close the opposite side, the body 22 and face plate 23 being provided with registering ears 24 perforated to receive bolts or other suitable fastening devices 25 by means of which the face plate of the casing may be secured in place. This casing is provided at its upper end with an opening 26 through which the pipe 21 leads, the lower end of the pipe extending somewhat below the center of the casing. The casing, at its lower end, is provided with forwardly and rearwardly directed, radial extensions 27 and 28, respectively, and the face plate 23 is similarly provided with extended portions to close such extensions. Each of the extensions is divided longitudinally at its outer end by an intermediately formed partition wall 29 and the casing and its face plate are both provided at points opposite these partitions with openings 30. Pipes 31 lead from the openings of the extension 27 on opposite sides of the locomotive to points immediately in advance of the forward drive wheels of the locomotive and above the rails 14 of the track. In like manner, pipes 32 lead from the openings of the extension 28 of the casing to points immediately at the rear of the rearward drive wheels and immediately above the rails 14. It will therefore be seen that if sand is permitted to flow from the upper portion of the sand dome through the pipe 21, and valve casing to the extension 27, such flow of sand will be divided by the partition wall 29 and will pass in equal quantities through the pipes 31 to the tracks in advance of the forward drive wheels of the locomotive. In like manner, if the flow of sand is so regulated as to pass into the extension 28 of the casing,

it will there be divided and fall by gravity onto the rails immediately behind the rear drive wheels 12.

One of the primary objects of our invention is the provision of an oscillatory valve mounted in the valve casing and not only controlling the flow of sand through the pipe 21, but also selectively controlling its discharge through the pipes 31 or 32, as desired. Referring more specifically to Fig. 4 of the drawings, it will be seen that this valve which, as a whole is indicated by the numeral 33, includes a hollow, substantially cylindrical body member adapted to seat closely within the valve casing. This valve 33 includes side portions 34 spaced from each other and maintained in proper relation by an integrally formed web or bottom portion 35 which connects the lower peripheral edges of the side portions. The radius of curvature of the upper edges of the side portions of the valve is substantially that of the valve casing, while the radius of curvature of the lower edges of said side portions is somewhat less, for a reason which will be hereinafter explained. The bottom portion 35 connects those edges having least radius of curvature and extends throughout a little more than 180° of the entire circumference of the side portions having radially directed extensions or stop shoulders 36 at its upper ends projecting flush with the adjacent ends of the upper edge portions of the sides 34. In effect, the valve is substantially a cylindrical pocket open throughout a little less than one-half of its peripheral edge and so formed as to provide the extensions or stop shoulders 36. In order to properly support the valve in place in the casing, that portion of the bottom of the casing between its extensions 27 and 28 is thickened internally as shown at 37 to bear against the bottom of the valve 33 and provide spaced valve engaging abutments. It will, therefore, be clear that upon oscillatory movement of the valve in either direction, one of its stop shoulders 36 will engage against the thickened portion of the valve casing to limit further turning movement of the valve. Such limiting of valve movement is clearly illustrated in Figs. 6 and 7 and any further description is therefore unnecessary.

It will of course be understood that the pipe 21 extends between the side portions of the valve or pocket and inasmuch as the lower end of said pipe is somewhat below the center of the valve casing, while the upper edges of the bottom portion 35 of the valve or pocket are somewhat above the center of the valve casing, the valve, when in normal position, as shown in Fig. 2 of the drawings, will form a pocket or sand trap for the reception of sand from the main portion of the sand dome. Furthermore, the sand in this pocket or trap will

effectually seal the lower end of the pipe 21 and prevent further flow of sand until the valve has been oscillated to permit discharge of its contents.

In order to provide means for manually oscillating the valve to control the flow of sand to the rails of the track, we provide the valve with a valve stem or shaft 38 which extends through an opening 39 formed centrally of the face plate 33 of the valve casing and which is firmly secured at its inner end to the central part of one of the sides 34 of the valve. A lever arm 40 is operatively connected to the outer end of this valve stem in such a manner as to preferably extend in vertical position when the valve is closed, that is, in the position shown in Fig. 2. A hand lever 41 is swingingly mounted at one end at any convenient point in the cab 13 of the locomotive and a connecting rod 42 joins the intermediate portion of this hand lever with the free end of the valve stem lever 40.

From the foregoing description, the operation of our improved gravity sander will be readily understood and but slight explanation is therefore necessary. In use, the upper portion of the sand dome 15 is filled with sand in the usual manner and a certain quantity of this sand immediately passes through the pipe 21 to fill the valve pocket 33. When it is desirable to sand the rails immediately in advance of the forward drive wheels 11 of the locomotive, the engineer or fireman swings the hand lever 41 forwardly as far as possible. This movement of the hand lever 41 acts through the connecting rod 42 and valve stem lever 40 to turn the valve 33 until one of its stop shoulders 36 engages the forward edge or abutment of the thickened portion 37 of the valve casing, that is, that portion of the valve casing adjacent the extension 27. When in this position, which is the position illustrated in Fig. 7 of the drawings, sand will pass freely from the valve or pocket into the extension 27 and being there divided will pass through the pipes 31 to the track rails. As soon as the sand commences to flow from the pocket or valve, the sand seal or trap is broken and sand will at once begin to flow from the sand dome through the pipe 21 for which reason a continuous flow of sand to the rails may be maintained, if desired, until all sand contained in the dome has been discharged. As soon as sufficient sand has been applied, the hand lever 41 is swung back to normal position to close the valve. Upon closing of the valve, sand continues to flow from the sand dome into the valve or pocket until such flow is stopped by filling of the pocket and sealing of the lower end of the pipe 21.

The operation in supplying sand to the rails immediately at the rear of the rear

drive wheels 12 is identical with that above described with the exception of the fact that the hand lever 41 is, of course, swung in the opposite direction to reversely turn the valve and permit discharge of its contents 70 into the extension 28 of the valve casing.

From the foregoing description, it will be apparent that we have provided an improved form of gravity sander which is economical in construction, readily installed and durable and effective in action.

It will of course be understood that we do not wish to be limited to the specific details of construction illustrated in the drawings and described in the specification, as various 80 minor changes, within the scope of the appended claims, may be made at any time, without in the slightest degree departing from the spirit of our invention.

Having thus described the invention, 85 what is claimed as new is:

1. A gravity sander including a valve casing having an inlet and two branched outlet ports, and an oscillatory valve in the casing movable to establish communication 90 between the inlet and either outlet port.

2. A gravity sander including a valve casing having an inlet and two branched outlet ports, pipes leading from the branches of the outlet ports, and a valve 95 mounted in the casing movable to establish communication between the inlet port and either outlet port.

3. In a gravity sander, the combination with a sand dome having a bottom, of a 100 valve casing positioned below the bottom and having spaced outlet ports, communicating means extending through the bottom of the sand dome and into the valve casing, and an oscillatory valve mounted 105 in the valve casing and movable to permit flow through either outlet port.

4. In a gravity sander, the combination with a sand dome having a bottom, of a 110 valve casing mounted below the bottom of the dome, said valve casing being provided with branched outlet ports, a valve mounted for oscillatory movement in the valve casing to permit selective discharge through either port, and a pipe leading from the 115 sand dome into the valve casing and terminating within the valve.

5. In a gravity sander, the combination with a sand dome having a bottom, of a 120 valve casing mounted below the bottom of the dome, said valve casing being provided with branched outlet ports, a valve mounted for oscillatory movement in the valve casing to permit selective discharge through either port, and a pipe leading from the 125 sand dome into the valve casing and terminating within the valve, said valve in normal position forming a trap limiting the flow of sand from the sand dome.

6. A gravity sander including a substan- 130

substantially cylindrical valve casing provided with spaced ported extensions, a substantially cylindrical valve mounted for turning movement in the casing, said valve being hollow and open along a portion of its peripheral edge to provide a pocket, and a supply pipe extending through the valve and into the opening of the pocket.

7. A gravity sander including a substantially cylindrical casing provided with spaced outlet ports and abutments adjacent the ports, a hollow cylindrical valve mounted for turning movement within the casing and including spaced side members and a bottom member, the valve being open at the top, stop shoulders formed upon the valve at the lower edges of said opening and adapted to engage the abutments to limit turning of the valve, and a supply pipe extending into the valve casing and between the side portions of the valve.

8. A gravity sander including a substantially cylindrical casing provided with spaced outlet ports and abutments adjacent the ports, a hollow cylindrical valve mounted for turning movement within the casing and including spaced side members and a bottom member, the valve being open

at the top, stop shoulders formed upon the valve at the lower edges of said opening and adapted to engage the abutments to limit turning of the valve, and a supply pipe extending into the valve casing and between the side portions of the valve, said pipe extending below the lower edges of the valve opening when the valve is in normal position.

9. A gravity sander including a substantially cylindrical valve casing provided with radially formed extensions, partition walls dividing the extensions, said extensions being provided with outlet ports upon either side of the partition walls, a pocket forming valve mounted for oscillation in the casing to discharge its contents into either extension, means for limiting the oscillation of the valve, and means for supplying sand to the valve.

In testimony whereof we affix our signatures in presence of two witnesses.
